UNITED STATES PATENT OFFICE.

MARTIN LANDENBERGER, JR., OF PHILADELPHIA, PENNSYLVANIA.

DESIGN FOR STOCKING FABRIC.

Specification forming part of Design No. 6,651, dated May 20, 1873; application filed May 6, 1873.

To all whom it may concern:

Be it known that I, MARTIN LANDENBERGER, Jr., of Philadelphia, Pennsylvania, have invented a Design for Stocking Fabric, of which the following is a specification:

My design for a stocking fabric, which is clearly illustrated by the figure in the accompanying drawing, consists of a series of parallel stripes, A, arranged at equal distances apart upon a plain ground, B, each of the said stripes being composed of a series of minor parallel stripes or ribs, a b c d, &c., the former of which is mottled, as shown, the others being plain, but of different shades or colors.

Irrespective of the colors employed, I claim—

The design for a stocking fabric, substantially as described, and as represented in and by the accompanying drawing.

In testimony whereof I have signed my name to this specification in the presence of two subscribing witnesses.

MARTIN LANDENBERGER, JR.
